SHOE SEWING MACHINE

Fred Ashworth, Wenham, and Carl F. Whitaker,
Beverly, Mass., assignors to United Shoe Ma-
chinery Corporation, Flemington, N. J., a cor-
poration of New Jersey

Application February 2, 1942, Serial No. 429,206

14 Claims. (Cl. 112—61)

The present invention relates to improvements in shoe sewing machines and is herein illustrated as embodied in a high speed lockstitch sewing machine of the hooked needle type, as disclosed in the present inventors' U. S. Letters Patent No. 2,271,611 of February 3, 1942, and constructed and arranged to sew the outsole and welted upper of a Goodyear welt shoe.

In the machine of the patent, the work is fed past the stitch forming devices by the operation of the work support and presser foot, which act to clamp the work and to move with the work the length of a stitch. Thereafter, the clamping pressure on the work is relieved and the presser foot and work support are back fed preparatory to clamping the work at a new location, the distance of a stitch length from the previous one.

In this machine, as in all outsole shoe stitching machines provided with a clamp feed, difficulty has been experienced in securing an accurate and uniform feeding of the work so as to produce a seam having the stitches accurately placed in the work and uniformly spaced. In machines of this type, especially when the machines are operated at high speeds, there is a tendency for the various parts of the presser foot actuating mechanism to vibrate and become more or less displaced as a result of lost motion or lack of rigidity in the connections and this tendency becomes more marked as the connections become worn during use.

One of the most practical and successful presser foot actuating mechanisms which has been used heretofore in this type of machine comprises a single floating cam actuated lever, which lever through suitable connections is connected at one point to the cam, at another point to the presser foot carrier and at still another point to a locking mechanism, which locking mechanism is actuated during each stitch forming cycle to lock the fulcrum of the floating lever from movement during the action of the cam on the lever to force the presser foot against the work and to lift the foot from the work, and which is also actuated to release the fulcrum of the floating lever to permit the lever to be moved about its cam connected end to force the presser foot yieldingly against the work. This type of presser foot actuating mechanism has also been successfully used in outsole stitching machines which are not provided with clamp feeding mechanism in which the work is fed by an awl or needle. In both types of machines, however, this construction of presser foot actuating mechanism has not proved entirely satisfactory, especially after the connec-

tions have become worn with use or when the machines are operated at high speed. A reason for the failure of these presser foot actuating mechanisms to operate satisfactorily is that the connections to the single floating lever are of such a nature and are so arranged as to cause the motion imparted to certain of the parts to be multiplied as this motion is imparted to another part and also to cause greater pressures to be exerted upon some of the connections than upon others both while the fulcrum of the floating lever is locked against movement and while it is unlocked. By reason of this inequality in the extent of the motions imparted to the various parts and in the pressures exerted upon the connections, the vibratory effects produced upon the parts and connections from any cause are increased in intensity and as they become excessive, cause the work to be improperly clamped in awl and needle feed machines and to be improperly clamped and fed in clamp feed machines.

The particular objects of the present invention are to provide a construction for a high speed lockstitch outsole shoe sewing machine in which accurate and equal feeding movements will be imparted to the work during sewing and in which the difficulties referred to will be avoided. In general, the objects are to simplify and improve the actuating mechanisms of an outsole sewing machine in a manner to insure accurate formation of stitches both in length and in uniformity with which they are set in the substance of an outsole where the machine is operated at high or moderate speeds, and to prevent irregularity in sewing operations of previous machines in which such irregularity has resulted from vibration, lost motion in the parts, or from other associated causes.

With these and other objects in view, a feature 40 of the present invention contemplates the provision, in a high speed outsole shoe stitching machine, of a mechanism for actuating the work clamping presser foot having its various parts constructed and arranged in an improved manner so as to occupy a minimum amount of space in the machine without interference with the desirable location and arrangement of the other stitch forming and work handling devices of the machine and also having its various parts constructed and arranged to distribute the pressures on the various connections and pivotal bearings to the best advantage so as to lessen wear on the bearings and connections and avoid looseness with consequent vibration in the parts. This improved presser foot actuating mechanism is of that type

hereinbefore referred to, in which a floating lever is provided in the connections from the presser foot and its actuating cam. In improving this type of presser foot actuating mechanism, the presser foot lever is pivotally mounted midway its length with equal arms and this lever is connected to the floating lever by means of a link joining a point on the floating lever and a point on the end of the presser foot lever remote from the presser foot and substantially in the right line passing through the work engaging face of the presser foot and the pivot of the presser foot lever. By pivotally mounting the presser foot lever midway its length and connecting its rear end to the floating lever in the manner stated, a simple compact construction is provided, enabling a presser foot spring to be connected to the floating lever between the points of its connection with the actuating cam and the presser foot, which arrangement does not interfere with the desired location of other parts of the machine and prevents any excessive pressure from being exerted on the pivotal bearing of the presser foot lever during operation of the machine. In order to still further economize in the amount of space occupied by the connections between the cam and the presser foot, the presser foot lever is mounted in the machine so as to have a substantially horizontal rearwardly extending arm and the floating lever which is directly connected by a link to the rear end of the presser foot lever is located above the rearwardly extending arm of the presser foot lever.

In accordance with another feature of the improved presser foot actuating mechanism, the fulcrum of the lever, instead of being mounted directly on a sliding support, as in prior constructions, is fulcrumed intermediate its ends on a supporting lever and the locking device for locking the fulcrum from movement and for releasing the fulcrum, is connected to the supporting lever at the opposite side of the fulcrum from the pivot of the lever. By this construction, the pressure on the locking devices is reduced, and by properly proportioning the arms of the floating and fulcrum supporting levers, the pressures at the ends of the floating lever and on the locking devices can be equalized. In the embodiment of the invention hereinafter specifically described, the floating lever and the fulcrum supporting lever are of the same length, and the floating lever is fulcrumed midway between the pivot of the supporting lever and its point of connection to the locking devices. The movements of both ends of the floating lever, while the fulcrum is locked against movement, are thus equal and any movement of the fulcrum support while unlocked imparts equal movements to the end of the floating lever connected to the presser foot lever and to the end of the fulcrum support connected to the locking devices. The position of the fulcrum of the floating lever is shifted, as in prior constructions, upon a change in the thickness of the work, and by reason of the construction above described, sufficient movement is imparted to the fulcrum support to permit the spring which forces the presser foot against the work while the fulcrum support is unlocked to act advantageously when connected to the fulcrum support. By this construction also, sufficient movement is imparted to the fulcrum support so that it can be advantageously connected to the thread measuring or pull-off mechanism. In the construction hereinafter described, both the actuating spring and the thread measuring mechanism

are connected to the fulcrum supporting lever and thereby the advantages are secured that the presser foot is not lifted by the cam against the tension of the spring during each stitch forming cycle and the connections from the thread measuring mechanism to the presser foot remain at rest until a change occurs in the thickness of the work, thereby eliminating the wear on these connections when vibrated during each stitch forming cycle, as in prior constructions.

In accordance with another feature of the presser foot mechanism hereinafter described, the point of connection of the cam actuated end of the floating lever is arranged to be substantially concentric with the fixed pivot of the fulcrum supporting lever while the presser foot is in a position of nearest possible approach to the work support, a stop being provided to limit the approach of the presser foot in this direction. In connection with this construction, means are provided for an adjustment of the fulcrum of the floating lever with relation to the supporting lever and thereby an adjustment of the position of nearest possible approach to the work support of the presser foot may be made without modifying the operation of the cam and of the spring when actuating the presser foot.

Other features of the invention consist in novel and improved devices, combinations and arrangements of parts hereinafter described and claimed, the advantages of which will be readily understood by one skilled in the art from the following description taken in connection with the accompanying drawings illustrating one embodiment of the invention.

In the drawings, Fig. 1 is a view in front elevation of a part of an outsole shoe sewing machine embodying the features of the present invention; Fig. 2 is a detail side view, partly in section, of the presser foot actuating mechanism and a portion of the work support with no work in the machine; Fig. 3 is a sectional plan view taken along the line 3-3 of Fig. 2; Fig. 4 is a sectional plan as viewed along the line 4-4 of Fig. 2; Fig. 5 is a sectional detail view of the presser foot lock device in front elevation; Fig. 6 is a detail view in front elevation of a portion of the presser foot actuating mechanism; Fig. 7 is a detail view, partly in section, of the work support carrier, its mounting shaft and feed actuating mechanism; Fig. 8 is a diagrammatic plan view on an enlarged scale illustrating the manner of obtaining the rearward pull on the work during work feed; Fig. 9 is a view in detail elevation, partly in section, of the work support and carrier; Fig. 10 is a side view on an enlarged scale of the upper part of the work support and a shoe guided thereby, shown in section; Fig. 11 is a view in side elevation of a portion of the work support and presser foot together with a novel form of back gage; Fig. 12 is a plan view of the work support and back gage; Fig. 13 is a perspective view of the sewing thread lock and pull-off actuating members; Fig. 14 is a sectional view of the same parts, taken along the line 14-14 of Fig. 1, together with the thread locks illustrating the manner of operation; Fig. 15 is a plan view of the looper actuating mechanism; Fig. 16 is a side view, partly broken away and in section, of the same parts; and Fig. 17 is a front view, partly broken away and in section, of the looper actuating mechanism.

The machine illustrated in the drawings is of the type disclosed in prior U. S. Letters Patent of Ashworth No. 1,169,909 of February 1, 1916.

No. 1,824,063 of September 22, 1931, and No. 2,015,654 of October 1, 1935, as well as in the Patent No. 2,271,611, above referred to. The machine is equipped with a curved hook needle 2, a needle guide 4 (see Fig. 11), a curved awl 6, a thread case 8 mounted within a shuttle or loop taker, needle threading mechanism including a looper 10 and a thread finger 12, a work support 14, a presser foot 16, back gage 18 and other stitch forming devices similar to those of the above patents, except as hereinafter pointed out. A driving and stopping mechanism also is provided for bringing the sewing shaft of the machine, indicated at 19, to rest with the work free to be removed. The general arrangement of the machine is as usual, with the sewing shaft located behind and above the point of operation of the stitch forming devices and substantially parallel to the line of the seam formed thereby.

The work is fed in the illustrated machine, as in the machine of Patents Nos. 1,824,063 and 2,271,611, by the movement of the work support and presser foot while clamping the work. During clamping engagement of the presser foot with the work, a measured amount of needle thread corresponding to the position of the presser foot is pulled off from the supply, the thread after measurement being locked against further movement towards or away from the supply until each stitch is set in the work.

As has been stated, the illustrated machine is provided with an improved presser foot actuating mechanism of the type comprising a floating lever in the connections between the presser foot and its actuating cam. As best shown in Fig. 2, the presser foot 16 is secured to the forward end of a substantially horizontal presser foot lever 24 pivotally mounted at 26 on the feed carriage to which is also secured the cooperating work support, as hereinafter described. The floating lever is indicated at 22, and in order to leave the space beneath the horizontally extending rear arm of the presser foot lever free to be occupied by other parts of the operating mechanism of the machine, is located above the presser foot lever. The fulcrum of the floating lever is located intermediate the ends of the lever and one end of the floating lever is connected directly to the rear end of the presser foot lever by a link 28 while the other end of the floating lever is connected to a cam actuated lever by an offset fork-ended link 52. The presser foot lever 24 is pivotally mounted midway its ends, and the point of connection between the rear end of the lever and the link 28 is such that the lever 24 is the equivalent of a straight lever with equal arms. Moreover, said point of connection is sufficiently close to the right line passing through the work engaging face of the presser foot and the pivot 26 that the lever can be actuated to clamp the work firmly without subjecting the pivot bearing to excessive pressure.

The supporting lever for the fulcrum of the floating lever is indicated at 20. This support, in the illustrated machine, is a frame resembling somewhat the letter H, and is pivotally mounted upon a pair of fixed pins 32 extending towards each other through bosses in angular bracket arms 3, one of which is attached to a cover plate 34 for a box 36 of the locking mechanism hereinafter described, and the other of which is connected to the machine frame. The lever 20 is arranged horizontally, and the pivot pins 32 engage the ends of the arms which extend forwardly from the cross bar of the H and which are separated sufficiently to permit the passage

between them of one end of the floating lever 22. The floating lever 22 is also arranged in a substantially horizontal position and is pivotally mounted between the arms of the lever 20 which extend rearwardly from the cross bar of the H, the fulcrum of the lever 22 consisting of a pin 30, the ends of which are supported by the arms of the lever 20.

The locking devices for locking the fulcrum of the floating lever from movement during each stitch forming cycle and for releasing the fulcrum are connected to the fulcrum supporting lever 20 at the opposite side of the fulcrum of the floating lever from the fixed pivot pins 32, upon which the supporting lever is mounted. As best shown in Figs. 2 and 3, one of the arms of the lever 20, extending rearwardly from the cross bar of the H, is of such length that a connection from the locking devices to the arm can be made at a point which is the same distance from the fulcrum of the floating lever as are the pivot pins 32. The link which connects the locking devices to the fulcrum supporting lever 20 is indicated at 56 and it will be noted, as clearly shown in Fig. 3, that this link is located at one side, in the direction of the seam line, of the link 28 connecting the floating lever 22 with the presser foot lever and that the arms of the levers 20 and 22 are also located side by side in the direction of the seam line. This arrangement of levers and connections provides a compact construction which leaves the space directly to the rear of the sewing point available for other operating connections in the machine and which, on account of the short length of each lever arm, has substantial rigidity.

The manner in which the illustrated construction acts to distribute the pressures on the various connections and pivot bearings will be apparent from an inspection of Fig. 2. Movements imparted to the floating lever about its fulcrum while the fulcrum is stationary move the ends of the lever equal distances and consequently the pressures on the connections at each end of the lever are the same. Also, the pressure on the fulcrum of the lever is twice the pressure at the ends of the lever. Due to the fact that the fulcrum of the floating lever 22 is midway the length of the supporting lever 20, the pressure on the locking devices connected to the rear end of the lever is one-half that on the fulcrum of the floating lever or the same as the pressure at each end of the floating lever. Also, any movement of the fulcrum of the floating lever, while the fulcrum supporting lever is unlocked, results in a movement of the connection to the locking devices twice that of the fulcrum.

In the illustrated construction, the spring which forces the presser foot against the work while the fulcrum supporting lever 20 is unlocked, is connected to act on the supporting lever between the points of a cam and presser foot connection at the same point as the locking devices, as hereinafter described, so that the presser foot is not lifted against the force of the spring. In forcing the presser foot towards the work support, the spring swings the fulcrum supporting lever 20 about its fixed pins 32 and during this movement the fulcrum, acting on the middle point of the floating lever 22, swings this lever about its pivotal connection with the link 52. As the lever 22 is thus swung, its rear end, which is connected by the link 28 to the presser foot lever, travels twice the distance of the fulcrum, or a distance equal to that traveled by the lock connected end of the fulcrum supporting lever 20.

The extent of movement and leverage provided by these connections results in an efficient and reliable adjustment of the presser foot to the thickness of the work in the machine.

In presser foot mechanisms of the type comprising a floating lever in the connections between the actuating cam and the presser foot, the fulcrum remains stationary during the cam actuated movements of the presser foot and changes its position only upon an increase or decrease in the thickness of the work. In the illustrated construction, this change in the position of the fulcrum of the floating lever is utilized to control the action of the thread measuring mechanism by which thread is pulled from the supply for each stitch, and to this end a connection hereinafter described is made from the thread measuring mechanism to the lock connecting end of the fulcrum supporting lever 20. As has been explained, this end of the lever 20 remains stationary except as a change occurs in the thickness of the work but has a range of movement twice that of the fulcrum whenever the fulcrum is moved. Accurate and reliable control of the thread measuring is secured by this construction and arrangement, and constant vibration of the controlling connections during sewing is avoided.

The cam lever for actuating the presser foot is similar to that of the machine in Patent No. 2,271,611 above identified and comprises a part 38 having a cam roll 40 and a part 42 having an arcuate slot 44. The two parts of the cam lever are fulcrumed loosely on a shaft 46 and joined together through a one-way yielding connection including an adjustable spring-pressed set screw 48 in the part 42. Adjustably clamped within the slot 44 on the lever part 42 is a releasable stud 50 forming a pivot for the upper end of the offset fork-ended link 52, best shown in Fig. 6, embracing the slotted portion of the cam lever at its upper end and surrounding an arm of the floating lever 22 at its lower end. The lower end of the link 52 is pivotally connected to the floating lever 22 by a pin 54 secured within the lever 22. Adjustment of the stud 50 along the slot 44 changes the work clamping and releasing action of the presser foot.

The presser foot lock of the present machine is similar to that disclosed in Patent No. 2,271,611 but is mounted with its lengthwise dimension in a substantially vertical position, as compared with an approximately horizontal position of the lock of said patent and with an angular position of the lock in the patent to Gouldbourn et al. No. 2,054,078 of September 15, 1936. The movable members of the lock are connected through a pair of parallel links 56 to the rearward arm of lever 20 which has the fixed fulcrum pivot. The upper ends of links 56 are disposed at the sides of lever 20, the point of pivotal connection being defined by the pin 58 and the lower ends of the links 56 carry a pin 60 passing through central and outer wedge members 62, the central one of which is disposed between the links 56 and the outer ones of which are located outside the links. The wedge members 62 are slidably mounted within the lock box 36 and are retained therein by the cover plate 34. Between the wedge members within the lock box are a spacing piece 64 and a series of steel locking rolls 66 at opposite sides of the central wedge member. The lower end of the series of rolls rests against a relatively fixed bar 68 in the lock box and the upper end is acted upon by a locking finger 70 secured to a shaft 72 hav-

ing bearings on the lock box. At one side of the lock box on the shaft 72 there is fixed a lock actuating arm 74 pivotally connected to a link 76 actuated yieldingly in a direction to cause the locking finger 70 to press the rolls 66 together and to render the lock effective. With the lock mounted in vertical position, the lock box holds the rolls 66 in such relation that the full weight of each roll acts directly on the one beneath to enable the lock to respond more quickly and positively when actuated.

To actuate the lock actuating link 76 rearwardly, the rearward reduced end is surrounded with a relatively heavy spring 78 compressed between a check nut 80 threaded on the reduced end of the link and a perforated bracket 82 through the perforation of which the link passes. The bracket 82, being secured to the frame of the machine, causes the link 76 to be drawn rearwardly until the locking finger engages the uppermost locking roll 66. To release the lock, the link 76 is moved forwardly against the force of the spring 78 and the locking rolls 66 are relieved of pressure by a cam actuated lever 84 fulcrumed on a cross shaft 86 secured to the frame of the machine. The upper arm of the cam lever has a roll engaging a cam on the sewing shaft 19 and on its lower arm is a forked portion cooperating with a flat surface 89 formed by a shoulder on the link 76.

The presser foot spring of the present machine is not connected directly to the floating lever 22, as in Patent No. 2,271,611, but acts on the floating lever through the links 56 connecting the equalizing lever 20 with the wedge members of the lock. To connect the spring to the links 56, the upper end of a C-shaped link 88 is pivotally connected between the links 56 by a bolt 90 and the lower forked end of the C-shaped link is perforated to receive a pin 92. The pin 92 also passes through the upper end of an H-shaped link 94 carrying a clamp bolt 96 at its lower end. The clamp bolt 96 is adjustably secured within an arcuate slot of a lever 98 fulcrumed on a shaft 100 and connected to the presser foot spring, indicated at 102, by a link 104 and a lever 106 mounted on a fixed stud 108. The presser foot spring 102 is connected at its rearward end to the lever 106 and extends forwardly towards the front of the machine frame where it is held under tension by means described in Patent No. 2,271,611.

The C-shaped link 88 and the H-shaped link 94 being under compression, are held in alignment by the action of the connecting pin 92 slidably arranged within a slot 110 (Fig. 2) in a downwardly projecting portion of one of the outer wedge members 62. The sides of the lock box 36 also are recessed to receive the ends of the pin 92, the pin acting against the upper edges of the recesses to limit the approach of the presser foot to the work. To prevent the pin 92 from sliding endwise through the recesses in the lock box, the downwardly extended slotted portion of said outer wedge member 62 carries a headed pin 112 which is received within a diametrical passage in the pin 92. The upper headed end of the pin 112 serves as a backing plate for a spring-pressed plunger 114 acting between the outer and central wedge members to take up lost motion between the wedge members and render the lock self-energizing, as indicated more fully in the patent to Gouldbourn et al.

The recesses in the lock box 36 are so formed

that when the pin 92 is in its highest position, that is, when the presser foot is in its position of nearest possible approach to the work, the pivot pins 32 and 54 are brought accurately into alignment. To overcome slight manufacturing irregularities, the floating pin 30 is provided with enlarged and reduced eccentric portions at its ends and the fulcrum supporting link 20 has mounted in it a clamp bolt 116 for securing the pin 30 against rotation in suitably adjusted position. When rotated manually in the link 20, the eccentric floating pin 30 will cause the presser foot to change its position of nearest approach to the presser foot without requiring change in the positions of the cam lever or lock.

For changing the amount of clamping force applied by the actuating cam lever 38, 42 to the presser foot, the clamp stud 50 is shifted along the slot 44 and to avoid the necessity of changing the adjustment of the eccentric pin 30 for each change in the position of the clamp stud in the slot 44, the slot 44 is made of arcuate shape concentric with the center of the pivot pin 54 when the presser foot is in its position of nearest possible approach to the work support, which position is determined by the engagement of the pin 92 against the upper end of the recesses in the lock box 36.

The shaft 100 not only forms a fulcrum for the lever 98, but also carries a thread measuring arm 119 similar to that of the machine disclosed in Patent No. 2,271,611 referred to, in accordance with the thickness of the work engaged by the presser foot. The thread measuring mechanism is thus controlled through connections to the rear end of the fulcrum supporting lever 20. To change the ratio by which the amount of thread measured varies with respect to the thickness of the work operated upon so that thread may be measured in an amount varying directly with the thickness of the work or varying at a lesser rate, as explained more fully in Patent No. 2,271,611, the slot which receives the clamp bolt 96 in the lever 98 is made eccentric to the pin 92 with the presser foot stopped by the pin 92 in its position of nearest approach to the work support, in which position the pivot pins 32 and 54 are in alignment. If the position of the clamp bolt 96 is changed while the parts are so located, no change in position of the spring or of the presser foot occurs so that the interengaging portions of thread in the stitches will always be set in the work in the same relation to the outer surfaces of the work while sewing the thinnest grades of work, the presser foot being at or approximately in its position of nearest approach to the work support under these circumstances.

The mechanism for imparting a feeding movement to the work support and presser foot while clamping the work is best shown in Figs. 7 to 10 inclusive. The general arrangement of this mechanism is the same as in the machine of Patent No. 2,271,611 and includes a cam 117 on the main sewing shaft, a cam lever 118, a link 120 connecting the cam lever with the central joint of a pair of toggle links 122 and 124. The toggle link 122 is pivotally mounted on a yoke 126 and the other link 124 is connected to a rearwardly extending arm on a feed carriage 128 of a shape having a lug for the pivotal mounting 26 for the presser foot lever 24. The particular construction of the present feed carriage differs slightly from that of Patent No. 2,271,611 in that the present carriage is formed as a single integral piece whereas the carriage of the said patent is

formed in two parts clamped together on an inclined pivot shaft corresponding to the shaft 130. The pivot shaft 130 is rotatably supported in bearings in the machine frame and is held from lengthwise movement by clamp collars 131 on the shaft.

As has been stated, one feature of the invention relates to an arrangement of the work support and presser foot to exert a continued rearward pull at right angles to the line of feed on the outsole of a shoe adjacent the point of sewing operations. In the embodiment of this feature, the work support 14 which is of U shape, is clamped to parallel portions of the feed carriage 128 and is formed along its work engaging surface with a raised portion 132 for causing the pressure exerted on the work to be centralized at a mid-point such as 134 on the portion 132 as the work is clamped by the presser foot. During feeding movements of the work support, the movements imparted to the work, unless otherwise prevented, are the same as the movements of the mid-point 134.

Referring to Fig. 8, the pressure centralizing portion 132 is indicated by a somewhat D-shaped outline and is located on the work support at the seam side of the needle and awl paths so that in feeding the work, it moves from the full-line position to the dot-dash line position further away from a point of intersection 135 between a line 136 passing through the center of the pivotal mounting shaft 130 at right angles to the line of feed indicated at 138, the line of feed passing through the needle and awl path. The needle and awl paths are coincident in the illustrated machine at the location of the awl 6. The awl 6 is located at the trailing point of the intersection 135, the pressure centralizing point 134 on the work support being located 40 still further to the left away from the intersection. As a result of the swinging movement of the work support about the shaft 130, the pressure centralizing point 134 moves appreciably out of the line of feed along an arcuate path 140 and rearwardly by a distance 142 in feeding the work. Since the work is clamped by the work support and presser foot during feeding movement, a rearward pull is exerted on the work itself. Back feeding movement of the work support and presser foot occurs when the clamping pressure of the foot is released from the work so that during back feeding movement, the pressure centralizing portion 132 of the work support moves from the hot-dash position to the full line position and forwardly by the distance 142. In the full line position of the pressure centralizing portion 132, the work is again clamped so that the rearward pull which is directed at right angles to the line of feed is continued from one sewing cycle to another, the awl being projected into and holding the work during each back feeding movement.

The rearward pull of the work support and presser foot on the work has further desirable results due to the inclination of the pivotal mounting shaft 130 for the feed carriage, as indicated in Fig. 9. In sewing about the shank of a Goodyear welt shoe 143, shown in Fig. 10, and about the entire marginal portion of other types of shoes, a front face 144 of the work support disposed at an angle to the work supporting and pressure centralizing surfaces serves as a gage against the outer last supported surface of the shoe upper indicated at 146. In a

Goodyear welt shoe, the shoe is presented by the operator in the position shown with the upper against the gaging surface 144 and with the projecting margin of welt 148 on the work supporting surface. The angle of the pivotal mounting shaft 130 is such that the forward movement of the work support during back feed of the work support causes the gaging surface 144 and the work supporting surface of the work support to be thrust with equal pressures against both the upper and welt. The inclination of the shaft 130 for this purpose is selected at an angle which will cause a line 150 bisecting the angle between the work gaging and supporting surfaces on the work support to intersect the axis of the shaft 130 at right angles, the forward thrust of the work support when so arranged being exerted along this line.

In order to enable the operator to hold the work against the back gage with little or no muscular effort, according to present day practices, a shoe is presented to the machine with the edges of the welt and outsole substantially out of parallel with the line of feed 138. During feeding movements of a shoe so presented to the present machine, there is a tendency to choke or retard the feeding movement of the shoe whenever a back gage for guiding the rearward edges of the work is employed. With the present construction and mode of operation, the rearward pull exerted by the work support and presser foot on the work enables the operator to present the work with the edge more nearly parallel to the line of feed than possible heretofore and at the same time, to hold the work against the back gage without substantial muscular effort.

As a means for accentuating the effects of rearward pull on the work, the feeding and back feeding movements are so proportioned that the time of feed is relatively long, as compared with the time of back feed. When the machine is operating at high speeds, the inertia of a shoe is easily overcome during the relatively long feeding movement and after the clamping pressure on the work is released, the relatively short back feeding movement enables a new clamping grip to be obtained on the work before any substantial forward movement of the work is possible.

Any link mechanism is subject to wear and looseness in its pivotal connections after long continued use and to offset the effects of wear in the work feeding mechanism of the present machine, the rearwardly extending arm of the feed carriage 128 is acted upon by a plunger 152 slidably in a passage in the machine frame and backed by a compression spring 154. The spring 154 is retained in the passage of the frame by a cap screw 156. By reason of the relatively long feeding movement imparted to the feed carriage by the feeding mechanism, it is possible for a light spring acting on the plunger 152 to take up all of the back lash in the feeding mechanisms even when the machine is operating at high speeds.

The back gage is similar to that of the machine disclosed in Patent No. 2,271,611 and is located with the end of its trailing work engaging edge in close proximity to the portion 132 of the work support which acts to concentrate the pressure on the work, as indicated in Fig. 12. With the end of the back gage so located, the operator is enabled to guide the work more effectively and

to change its position easily while presenting the work to the machine.

To prevent the outer lower corner of the welt from becoming wedged or cut between the work support and the back gage as the work is compressed by the presser foot, the present back gage is provided with a lip 158 having a horizontal work engaging surface in front of the vertical work engaging portion of the back gage, as shown in Figs. 11 and 12. The angularly disposed surfaces formed by the lip 158 and the vertical edge engaging surface of the back gage provide a trough which the outer lower corner of the welt travels. To enable the lip to approach as close as possible to the work engaging surface of the work support, the work support is cut away at 160 to form a shoulder 162. During back feed movement of the work support, the shoulder 162 moves towards the lip on the back gage and raises the edge of the welt onto the surface of the work support.

Like the machine of Patent No. 2,271,611 the illustrated machine has a pull-off actuating mechanism including a curved slotted arm 164 (see Figs. 13 and 14) rotatably mounted on a shaft 166 in alignment with the thread measuring shaft 100 and acting between a pair of guides on the measuring arm 119 to draw off a supply of needle thread sufficient for each stitch. Also mounted on the shaft 166 are a pair of thread lock actuating arms 168 and 170. These arms are formed with cam surfaces at their extremities which cooperate with shoes 112 and 174 for clamping the thread at either side of the pull-off against thread guide rolls 176 and 178. The pull-off and thread lock arms of the machine in the patent last referred to are secured to the shaft and to concentric sleeves, one inside the other on the shaft 166. During rotation of the shaft to actuate the pull-off arm corresponding to the arm 164, there is a tendency for the shaft to impart movements to the cam arm supporting sleeves so as to interfere with proper operation of the thread locks or to open one of the locks temporarily when it should be closed.

In order to prevent interference between the pull-off arm and insure proper operation of the locks in the illustrated machine, the pull-off arm 164 and lock actuating arms 168 and 170 are constructed and arranged to oscillate on the cross shaft 166 in such a way that no pressure radially of the shaft will be transferred from one to another. Instead of mounting the pull-off arm directly on the shaft 166 and the lock actuating arms on sleeves supported one inside of the other, all of the arms are rotatable directly on the shaft 166 and are connected with their actuating mechanisms by means of struts 180, 182 and 184. The strut 180 connects the pull-off arm with an integrally formed yoke 186 acting as a bearing member for the pull-off actuating arm 168 extending from the yoke. Between the bearing portions of the yoke is a second bearing member 190 having an arm 192 for operating the lock actuating arm 168. The strut 184 connects the lock actuating arm 170 with a bearing member 194 having an operating arm 196. The lock actuating arm 168 thus has triplicate bearings directly on the shaft 166 and the pull-off and other lock actuating arms 170 and 164 have double bearings spaced along the shaft so that actuation of any of the arms will not affect any of the others. The cross shaft 166 itself is fixed in a bracket 198 secured to the frame of the machine and having two shaft 75 supporting bosses, one at the right end of the

shaft 166 and one at an intermediate position between the bearing members connected by the struts.

The mechanism for actuating the looper 10 of the present invention is constructed to move in a curving path generally in the line of feed, as in the machine of the Patent No. 2,271,611 and to avoid application of excessively heavy forces in any of its individual parts, ample bearing surfaces being provided for extreme durability in use. The looper proper is in the usual form with an upstanding perforated thread receiving stem and in its present form is clamped to a two-part carrier 200 slideable lengthwise along an arm 202 provided with rectangular guiding surfaces inside the carrier, the lower edges of the carrier having flanges engaging grooves in the arm. The parts of the carrier are secured together at the forward end by a bolt 204 which secures the stem of the looper to the carrier and at its rearward end by a threaded stud and nuts 206 passing through the carrier parts and a block 208 of a shape corresponding to that of the arm 202. The arm 202 swings on a pivot pin 210 having a conical wear compensating portion fitting a corresponding opening in the carrier and clamped within a supporting bracket 212 secured to the machine frame. Swinging of the arm on its pivot pin causes the perforated end of the looper to move to the right and left of the needle. To impart a forward and rearward component of movement to the looper during the swinging movement of the arm 202, block 208 has clamped therein a headed pin 214 on which is rotatable a conical roll 216 engaging an S-shaped cam slot 217 formed in the bracket 212. The central portion of the bracket is recessed at 218 to provide space for a pin 220 having a conical wear compensating head fitting a correspondingly shaped opening in the arm 202. The pin 220 is secured within one end of an actuating link 222 pivotally connected to a cam lever 224 fulcrumed at 226 on a fixed vertical shaft. The cam lever 224 is provided with a roll 228 engaging a cam 230 on the sewing shaft 19.

Certain of the mechanisms which have been illustrated and described are not claimed herein but form the subject-matter of divisional applications, the looper actuating mechanism being claimed in application Serial No. 488,966, filed May 29, 1943, the pull-off and thread lock actuating mechanism being claimed in application Serial No. 496,464, filed July 28, 1943, and the work feeding and edge gage mechanism being claimed in application Serial No. 498,484, filed August 13, 1943.

The nature and scope of the invention having been indicated and a particular embodiment of the invention having been described, what is claimed is:

1. An outsole shoe stitching machine having, in combination, stitch forming devices, a work support, a presser foot, mechanism for actuating the presser foot comprising a presser foot lever pivotally mounted midway its length at one end of which lever the presser foot is mounted, an actuating cam, a floating lever, a connection from the cam to a point on the floating lever, a link directly connecting another point on the floating lever to the end of the presser foot lever remote from the presser foot at a point to form equal arms on the presser foot lever, locking devices for locking the fulcrum of the floating lever from movement, means for actuating the locking devices to lock and release the fulcrum during each

stitch forming cycle, and a spring acting on the floating lever between the points of connection with the cam and the presser foot to press the foot towards the work support while the fulcrum of the floating lever is released.

2. An outsole shoe stitching machine having, in combination, stitch forming devices, a work support, a presser foot, mechanism for actuating the presser foot comprising a presser foot lever pivotally mounted midway its ends and having a substantially horizontal rearwardly extending arm on the forward end of which lever the presser foot is mounted, an actuating cam, a floating lever located above the rearwardly extending arm of the presser foot lever, a connection from the cam to a point on the floating lever, a link directly connecting the rear end of the presser foot lever to another point on the floating lever, locking devices for locking the fulcrum of the floating lever from movement, means for actuating the locking devices to lock and release the fulcrum during each stitch forming cycle, and a spring acting on the connections between the cam and the presser foot to press the foot towards the work support while the fulcrum is released.

3. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a supporting lever on which the floating lever is fulcrumed, a connection from the cam to a point on the floating lever, a connection from the presser foot lever to another point on the floating lever, locking devices for locking the fulcrum supporting lever from movement, means for actuating the locking devices to lock and release the fulcrum supporting lever during each stitch forming cycle, and a spring acting on the floating lever between the points of cam and presser foot connection to press the foot towards the work support while the fulcrum of the floating lever is released.

4. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a fulcrum supporting lever on which the floating lever is fulcrumed intermediate its ends, a connection from the cam to a point on the floating lever at one side of its fulcrum, a connection from the presser foot lever to a point on the floating lever at the opposite side of its fulcrum, locking devices for locking the fulcrum supporting lever from movement, means for actuating the locking devices to lock and release the fulcrum supporting lever during each stitch forming cycle, and a spring acting on the floating lever between the points of cam and presser foot connection to press the foot towards the work support while the fulcrum of the floating lever is released.

5. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a ful-

crum supporting lever pivoted at one end of the same length as the floating lever, at the central point of which the floating lever is fulcrumed midway its length, a connection from the cam to one end of the floating lever, a connection from the presser foot lever to the other end of the floating lever, locking devices for locking the fulcrum supporting lever from movement, a connection from the locking devices to the end of the fulcrum supporting lever remote from its pivot, means for actuating the locking devices to lock and release the fulcrum during each stitch forming cycle, and a spring acting on the connections between the cam and the presser foot to press the foot towards the work support while the fulcrum is released.

6. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a fulcrum support on which the floating lever is fulcrumed intermediate its ends a connection from the cam to a point on the floating lever at one side of its fulcrum, a connection from the presser foot lever to a point on the floating lever at the opposite side of its fulcrum, locking devices for locking the fulcrum support from movement, means for actuating the locking devices to lock and release the fulcrum support during each stitch forming cycle, a spring acting on the connections between the cam and the presser foot to press the foot towards the work support while the fulcrum support is released, and thread measuring mechanism comprising a thread measuring arm and a connection from the thread measuring arm to the fulcrum support for moving the thread measuring arm upon movement of the fulcrum support while released.

7. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a fulcrum support on which the floating lever is fulcrumed intermediate its ends, a connection from the cam to a point on the floating lever at one side of its fulcrum, a connection from the presser foot lever to a point on the floating lever at the opposite side of its fulcrum, locking devices for locking the fulcrum support from movement, means for actuating the locking devices to lock and release the fulcrum support during each stitch forming cycle, a spring acting on the connections between the cam and the presser foot to press the foot towards the work support while the fulcrum support is released, a thread pull-off mechanism, and a connection from the pull-off mechanism to the fulcrum support acting to vary the amount of thread pulled from the supply with variations in the position of the fulcrum support of the floating lever.

8. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a fulcrum supporting lever on which the floating lever has a fulcrum, locking devices for locking

the fulcrum supporting lever from movement, means for actuating the locking devices to lock and release the fulcrum supporting lever during each stitch forming cycle, a spring acting on the connections between the cam and the presser foot to press the foot towards the work support while the fulcrum supporting lever is released, a thread pull-off mechanism, and a connection from the pull-off mechanism to a point on the fulcrum supporting lever on the opposite side of its fulcrum from the pivot of the fulcrum supporting lever to vary the amount of thread pulled from the supply with variations in the position of the fulcrum of the floating lever.

9. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a fulcrum supporting lever mounted on a fixed pivot, on which lever the floating lever is fulcrumed, locking devices for locking the fulcrum supporting lever from movement, means for actuating the locking devices to lock and release the fulcrum supporting lever during each stitch forming cycle, a spring acting on the connections between the cam and the presser foot to press the foot towards the work support while the fulcrum support is released, a connection from the presser foot lever to a point on the floating lever, and a connection from the cam to another pivot point on the floating lever, which point is substantially concentric with the fixed pivot of the fulcrum supporting lever while the presser foot is in a position of nearest possible approach to the work support.

10. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a fulcrum supporting lever mounted on a fixed pivot on which lever the floating lever is fulcrumed, locking devices for locking the fulcrum supporting lever from movement, a connection from the locking devices to the end of the fulcrum supporting lever remote from its pivot, means for actuating the locking devices to lock and release the fulcrum during each stitch forming cycle, a spring acting on the connections between the cam and the presser foot to press the foot toward the work support while the fulcrum is released, and means for adjusting the fulcrum of the floating lever on the fulcrum supporting lever.

11. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a fulcrum supporting lever mounted on a fixed pivot, on which lever the floating lever is fulcrumed, locking devices for locking the fulcrum supporting lever from movement, means for actuating the locking devices to lock and release the fulcrum supporting lever during each stitch forming cycle, a spring acting on the connections between the cam and the presser foot to press the foot towards the work support while the fulcrum supporting lever is released, a connection from the

presser foot lever to a point on the floating lever, a connection from the cam to another point on the floating lever, which pivot point is substantially concentric with the fixed pivot of the fulcrum supporting lever while the presser foot is in a position of nearest possible approach to the work support, connections from the locking devices to the end of the fulcrum supporting lever remote from its pivot, and means for limiting the movement of said locking connections in a direction to prevent movement of the presser foot towards the work support beyond the position where the connecting point of the floating lever to the cam is concentric with the fixed pivot of the fulcrum supporting lever.

12. An outsole shoe stitching machine having, in combination, stitch forming devices, a work support, a presser foot, presser foot actuating mechanism comprising a presser foot lever on which the presser foot is mounted, an actuating cam, connections between the cam and the presser foot lever comprising a floating lever, a fulcrum supporting lever mounted on a fixed pivot on which lever the floating lever is fulcrumed, locking devices for locking the fulcrum supporting lever from movement, a connection from the locking devices to the end of the fulcrum supporting lever remote from its pivot, means for actuating the locking devices to lock and release the fulcrum supporting lever during each stitch forming cycle, a spring acting on the connections between the cam and the presser foot to press the foot toward the work support while the fulcrum is released, a cam actuated lever having an arm formed with an arcuate slot, a link pivotally connected at one end to the floating lever and adjustably connected to the slotted arm of the cam actuated lever, and means for stopping the movement of the fulcrum supporting lever while released in a position in which the point of pivotal connection of said link with the floating lever is concentric with the arcuate slot in the cam actuated lever.

13. An outsole shoe stitching machine having,

in combination, stitch forming devices, a work support, a presser foot, presser foot actuating mechanism comprising a presser foot lever on which the presser foot is mounted, an actuating cam, connections between the cam and the presser foot lever comprising a floating lever, a fulcrum support on which the floating lever is fulcrumed, locking devices for locking the fulcrum support from movement, means for actuating the locking

5 devices to lock and release the fulcrum support during each stitch forming cycle, and a spring acting on the connections between the cam and the presser foot to press the foot towards the work support while the fulcrum support is released, said 10 locking devices comprising a wedge member connected to the fulcrum support, a series of rolls for locking the wedge member, and a lock box within which the wedge member and rolls are contained with the series arranged in substantially 15 vertical position with the weight of one roll acting directly on the roll beneath.

14. An outsole shoe stitching machine having, in combination, stitch forming devices, a work support, a presser foot, presser foot actuating 20 mechanism comprising a presser foot lever on which the presser foot is mounted, an actuating cam, connections between the cam and the presser foot lever comprising a floating lever, a fulcrum supporting lever on which the floating lever is fulcrumed, locking devices for locking the fulcrum supporting lever from movement, means for 25 actuating the locking devices to lock and release the fulcrum supporting lever during each stitch forming cycle, and a spring acting on the connections 30 between the cam and the presser foot to press the foot towards the work support while the fulcrum is released, the floating lever and the fulcrum supporting lever having arms disposed side by side in the direction of the seam line with the 35 arm of the floating lever connected to the presser foot lever and the arm of the fulcrum supporting lever connected to the locking devices.
